ENGINE CONTROLLING APPARATUS

Joseph W. Allen, East Orange, N. J., assignor, by
mesne assignments, to Eclipse Aviation Corporation,
East Orange, N. J., a corporation of New Jersey

Application September 29, 1932, Serial No. 635,426

11 Claims. (Cl. 290—38)

This invention relates to engine controlling apparatus and more particularly to means for inter-relating the operation and control of the ignition and starting mechanism of an internal combustion engine.

An object of the invention is to provide inter-related control mechanism of the foregoing character operative to automatically start an internal combustion engine simultaneously with the energization of the ignition circuit, and further operative to automatically de-energize the starting motor after a brief interval of predetermined duration, measured from the initial energization of the ignition circuit.

Another object of the invention is to provide time delay means of the foregoing character which is further operative to re-energize the starting motor following a stall, the re-energizing means being operative after a brief interval of predetermined duration, measured from the first moment of stall.

Another object of the invention is to provide novel means for utilizing electrical energy derived from the ignition circuit of an internal combustion engine for the purpose of controlling the time of energization and de-energization of the electrical parts of an engine starting mechanism. In this connection, a feature of the invention is the use of a unidirectional condenser electrically associated with the ignition and starting circuits in such manner that energy from the primary winding of the induction circuit, which is produced by the collapse of the magnetic field created by the periodic interruptions of current flowing therein, is stored in said condenser and subsequently transferred to an electro-magnetic device exercising an influence upon the starting circuit.

These and other objects and advantages to be derived from the use of the invention will appear more fully hereinafter from a consideration of the detailed description and the accompanying drawing illustrating one embodiment of the invention. It is to be expressly understood, however, that the drawing is for the purpose of illustration only and is not designed as a definition of the limits of the invention, reference being had primarily for this purpose to the appended claims.

In the drawing,

Fig. 1 is a schematic representation of the novel instrumentalities in which the present invention is preferably embodied; and

Fig. 2 is a view in section of one form of condenser suitable for use in the circuit shown in Fig. 1.

In the drawing, the invention is shown as applied to certain accessories of an internal combustion engine, such as a battery 6, or equivalent source of electrical energy, a starting motor 7, and a spark plug 8 constituting one of a series corresponding in number to the number of cylinders of the engine, a portion of the wall of one of which is shown at 9. The means for producing sparks periodically across the electrodes of plugs 8 may be of any conventional form, but preferably includes a distributor shown diagrammatically at 12 and 13, the former character indicating the stationary contacts electrically connected with the various spark plugs, and the latter reference character indicating the rotating contact electrically connected with the secondary winding 16 of the induction coil 17, the said arm 13 being rotatable with a shaft 18 connected in the usual manner to rotate in timed relation with the cam 19 which periodically interrupts the circuit of the primary winding 21 of the induction coil by separating the contacts 22 and 23, the latter being grounded as indicated at 24, and the former connecting with the induction coil as indicated by the conductor 26.

To this conductor 26 there is connected a second conductor 28 leading to the terminal or terminals 29 of a unidirectional condenser 30 which may take the form indicated in Fig. 2, the opposite terminal 31 of the condenser being connected to the winding 34 of an electro-magnetic device 36, and from the winding to the ground 35. Solenoid 36 is shown as having a magnetizable core 37 normally held in the position shown by suitable mechanical means, such as the spring 38, and adapted to be withdrawn from such position upon the creation of a sufficiently strong magnetic flux coursing through the said core 37. As shown, there is mechanically connected to the core 37, and insulated therefrom, a contact plate 41 normally bridging a pair of stationary contacts 42 and 43, the latter being grounded as indicated at 44, and the former connecting with one end of the winding 46 of a second electro-magnetic device 47, also shown as in the form of a solenoid having a plunger 48 normally held by the spring 49 in the position indicated in Fig. 1, in which position the circuit closing contact 51 connected therewith is out of engagement with a pair of stationary contacts 52 and 53, the former of which connects by means of a wire 56 with the positive terminal 57 of the battery 6, while the latter contact connects by means of wire 58 with one side of the armature of the starting motor 7, the other side being grounded as indicated at 59.

Preferably the switch 62, which corresponds to the conventional ignition switch usually mounted in a position conveniently accessible to the operator of the vehicle in which the engine is installed, 5 has in the present instance the additional function of controlling the flow of current to the condenser, as well as to the solenoids 36 and 47 above described. To this end there is provided an arcuate conducting strip 66 engageable by the switch 10 arm 62 to electrically connect the lead 68 with both lead 69 and the lead 72, as indicated. The lead 72 is shown as extending to winding 21 of the induction coil, and by means of the branch lead 28 to the condenser 30 and solenoid 36, while 15 the lead 69 connects with the solenoid winding 46, as indicated.

As above stated, the condenser is preferably of the unidirectional type, one such type of condenser being shown in Fig. 2, which is a reproduction 20 of the electrolytic condenser disclosed in the Mershon Patent No. 1,784,674.

This condenser construction is suitable for the present invention in that it permits the inductive surges resulting from the periodic collapse of the 25 magnetic field of the induction coil to be collected on the electrodes 75 of the condenser, charging the same to a substantial potential, which in installations thus far made has been of the magnitude of approximately 45 volts when using a 30 condenser of 8 mfd. capacity.

When it is desired to start the engine, the operator throws the switch 62 to closed position, thereby 35 electrically connecting each of the conductors 69 and 72 with the battery. In view of the fact that full battery voltage is immediately effective across the terminals of winding 46, switch 51 is promptly moved to closed position, while the resulting magnetic flux through the core 37 of the solenoid 36 is insufficient to open the switch 41 40 immediately, and a time interval of definite duration (as predetermined by the electrical characteristics of the condenser and coils) elapses. During this interval the switch 51 remains closed by reason of the continued energization of the coil 45 46. This closure of the switch 51 causes current to flow to the starting motor 7 and the starting mechanism energized thereby (not shown herein) is effective to start rotation of the engine crank-shaft and resulting operation of the distributor 50 13, interrupter 19, and other parts of the ignition system, in the usual manner.

The engine is thus brought into a condition 55 wherein the ignition and carbureting mechanism become capable of maintaining it in operation, independently of any aid from the starting motor 7. De-energization of said motor thereafter occurs (that is, at the end of the predetermined time interval required for fully charging the condenser) and the switch 41 is opened as a result of 60 the increased strength of the magnetic field acting through core 37 due to discharge of the condenser through the winding 34. This in turn de-energizes solenoid 47, permitting spring 49 to open the switch 51.

65 Thereafter, at any time when an increase in load or decrease in supply of fuel causes the engine to stall, thereby discontinuing the periodic interruptions of the current in the primary winding, the electrical energy which has been accumulating in the condenser during such periodic interruptions drops off correspondingly and soon becomes ineffective to maintain the coil 34 fully energized. Thereupon the spring 38 becomes effective to reclose the switch 41 and the solenoid 70 75 47 is accordingly re-energized, thereby closing

the switch 51, and causing re-energization of the starting motor 7 and a re-cracking of the engine, it being assumed that the switch 66 has remained in the closed position. The resumed operation of the interrupter 19 causes resumption of the process of storage of energy in the condenser, and the re-energization of the winding 34 reopens the switch 51, thus repeating the first stage of the cycle of operation previously described.

80 There is thus disclosed a novel engine control- 85 system wherein the ignition and starting are under the control of a single manually operable instrumentality, and the said functions are so inter-related as to produce energization and de-energization of both in proper timed relation. 90

What is claimed is:

1. In a system for starting an internal combustion engine, a starting motor, a battery, a circuit connecting said battery and motor, said circuit including a normally open switch, a solenoid 95 adapted when energized to close said switch, an ignition circuit including an induction coil having primary and secondary windings, means for simultaneously energizing said solenoid and closing said ignition circuit, and means including a 100 second solenoid responsive to interruption of the current flow through said primary winding to de-energize said first named solenoid.

2. In a system for starting internal combustion engines including a starting motor and a battery, 105 a circuit connecting said motor and battery, an ignition circuit, a single switch controlling the closure of said starting motor and ignition circuits, and means including a condenser operated by energy drawn from said ignition circuit for 110 rendering said single switch ineffective.

3. In a system for starting an internal combustion engine, a starting motor, a battery, a circuit connecting said battery and motor, said circuit including a normally open switch, a solenoid 115 adapted when energized to close said switch, an ignition circuit including an induction coil having primary and secondary windings, means for simultaneously energizing said solenoid and closing said ignition circuit, means including a 120 second solenoid operated by energy drawn from said ignition circuit to de-energize said first named solenoid, said last named means including a condenser which is first charged by the energy drawn from the ignition circuit and thereafter 125 discharged through the winding of said second solenoid.

4. In a system for starting an internal combustion engine, a starting motor, a battery, a circuit connecting said battery and motor, said circuit 130 including a normally open switch, a solenoid adapted when energized to close said switch, an ignition circuit including an induction coil having primary and secondary windings, means for simultaneously energizing said solenoid and closing 135 said ignition circuit, means including a second solenoid operated by the energy drawn from said ignition circuit at the moment of interruption of the current flow through said primary winding to de-energize said first named solenoid, 140 said last named means including a condenser which is first charged by the energy drawn from the ignition circuit and thereafter discharge through the winding of said second solenoid.

5. In a system for starting internal combustion 145 engines including a starting motor and a battery, a circuit connecting said motor and battery, an ignition circuit including an induction coil having primary and secondary windings, a circuit circuit interrupting device in series with said pri- 150

- mary winding, a single switch controlling the closure of said starting motor and ignition circuits, means including a solenoid operated by energy drawn from said ignition circuit for rendering said single switch ineffective to maintain said starting motor energized after a brief interval of predetermined duration, measured from the initial energization of said ignition circuit, said last named means including a condenser which is first charged by the energy drawn from the ignition circuit and thereafter discharged through the winding of said solenoid. 5
6. In a system for starting internal combustion engines including a starting motor and a battery, a circuit connecting said motor and battery, an ignition circuit including an induction coil having primary and secondary windings, a circuit interrupting device in series with said primary windings, a single switch controlling the closure of said starting motor and ignition circuits, and means including a solenoid operated by energy drawn from said ignition circuit at the moment of interruption of the current flow through said primary winding for de-energizing said solenoid 10 for rendering said single switch ineffective to maintain said starting motor energized after a brief interval of predetermined duration, measured from the initial energization of said ignition circuit, said last named means including a condenser which is first charged by the energy drawn from the ignition circuit and thereafter discharged through the winding of said solenoid. 15
7. In a system for starting an internal combustion engine, a starting motor, a battery, a circuit connecting said battery and motor, said circuit including a normally open switch, a solenoid adapted when energized to close said switch, an ignition circuit including an induction coil having primary and secondary windings, means for simultaneously energizing said solenoid and closing said ignition circuit, means including a second solenoid operated by energy drawn from said ignition circuit to de-energize said first named solenoid, said last named means including a condenser which is first charged by the energy drawn from the ignition circuit and thereafter discharged through the winding of said second solenoid, and means effective upon a complete discharge of said condenser to re-energize said starting motor circuit. 20
8. In a system for starting an internal combustion engine, a starting motor, a battery, a circuit connecting said battery and motor, said circuit including a normally open switch, a solenoid adapted when energized to close said switch, an ignition circuit including an induction coil having primary and secondary windings, means for simultaneously energizing said solenoid and closing said ignition circuit, means including a second solenoid operated by the energy drawn from said ignition circuit at the moment of interruption of the current flow through said primary winding to de-energize said first named solenoid, said last named means including a condenser which is first charged by the energy drawn from the ignition circuit, and thereafter dis- 25
- charged through the winding of said second solenoid, and means effective upon a complete discharge of said condenser to re-energize said starting motor circuit. 30
9. In a system for starting internal combustion engines including a starting motor and a battery, a circuit connecting said motor and battery, an ignition circuit including an induction coil having primary and secondary windings, a circuit interrupting device in series with said primary winding, a single switch controlling the closure of said starting motor and ignition circuits, and means including a solenoid operated by energy drawn from said ignition circuit for rendering said single switch ineffective to maintain said starting motor energized after a brief interval of predetermined duration, measured from the initial energization of said ignition circuit, said last named means including a condenser which is first charged by the energy drawn from the ignition circuit and thereafter discharged through the winding of said solenoid, and means effective upon a complete discharge of said condenser to re-energize said starting motor circuit. 35
10. In a system for starting internal combustion engines including a starting motor and a battery, a circuit connecting said motor and battery, an ignition circuit including an induction coil having primary and secondary windings, a circuit interrupting device in series with said primary winding, a single switch controlling the closure of said starting motor and ignition circuits, and means including a solenoid operated by energy drawn from said ignition circuit at the moment of interruption of the current flow through said primary winding for de-energizing said solenoid for rendering said single switch ineffective to maintain said starting motor energized after a brief interval of predetermined duration measured from the initial energization of said ignition circuit, said last named means including a condenser which is first charged by the energy drawn from the ignition circuit and thereafter discharged through the winding of said solenoid, and means effective upon a complete discharge of said condenser to re-energize said starting motor circuit. 40
11. In a system for starting internal combustion engines including a starting motor and a battery, a circuit connecting said motor and battery, an ignition circuit including an induction coil having primary and secondary windings, a circuit interrupting device in series with said primary windings, a single switch controlling the closure of said starting motor and ignition circuits, and means including a solenoid operated by energy drawn from said ignition circuit at the moment of interruption of the current flow through said primary winding for de-energizing said solenoid for rendering said single switch ineffective to maintain said starting motor energized after a brief interval of predetermined duration measured from the initial energization of said ignition circuit, said last named means including a condenser which is first charged by the energy drawn from the ignition circuit and thereafter discharged through the winding of said solenoid, and means effective upon a complete discharge of said condenser to re-energize said starting motor circuit. 45
